[57] **CLAIM**

The ornamental design for a table pedestal, as shown and described.

DESCRIPTION

FIG. 1 is a perspective view of a table pedestal showing my new design;

FIG. 2 is a corner side elevational view thereof, the other three corner side elevational views being identical to that shown;

FIG. 3 is a front elevational view thereof, the rear elevational view and the left and right side elevational views being identical to that shown;

FIG. 4 is a view taken along line 4—4 in FIG. 3, showing the upper portion of the pedestal; and,

FIG. 5 is a view taken along line 5—5 in FIG. 3, showing the lower portion of the pedestal.

The broken line showing of the table top and top surface of the pedestal are for environmental purposes only and form no part of the claimed design.
